UNITED STATES PATENT OFFICE

EBER J. HAYMAN, OF PARKERSBURG, WEST VIRGINIA

JOINT FOR METALLIC MEMBERS

Application filed September 26, 1927. Serial No. 222,006.

My present invention relates to a joint for metallic members which is particularly adapted for locking together metal sheets in the formation of a tin or metal roof.

The principal object of the invention is the provision of a joint of the type described which will be water-tight, which will permit of the sheets being secured to the wooden roof sheathing without the securing means passing through the sheets themselves, and which provides a lock for the abutting parts.

Other important objects of the invention are the provision of a construction which will permit ready separation of the parts should the same be necessary without mutilation of the metal strips so that they may be used again.

To this end the invention contemplates a metal joint comprising two longitudinally extending elements such as the metal sheets commonly used in the formation of a tin or metal roof. One of these elements is a wall portion upstanding from its main body, the wall portion having its marginal extremity bent or returned toward the body portion. This bend may be either sharp or arcuate. Lying adjacent the first mentioned element is a second element of like character also having an upstanding wall lying adjacent the upstanding wall of the first mentioned element and having its marginal portion bent over the margin of the first mentioned element. An offset lock is provided in the marginal portion of the second element which resiliently engages the raw or actual edge of the underlying margin. Underlying the main body of the second mentioned element is a cleat or fastening means adapted to be nailed to the wooden sheathing of the roof, which cleat has a bent portion overlying the margin of the first mentioned element, thus securing this member to the roof. The fact that the second mentioned element is locked to the first element thus fastens both elements to the roof without any securing means penetrating either of the elements.

The invention further consists in the novel arrangement, construction and combination of parts hereinafter described and shown in the accompanying drawings, in which:—

Fig. 1 is a sectional view of a device em-

bodying the preferred form of my invention.

Fig. 2 is a side elevation of Fig. 1.

Fig. 3 is a perspective view of a complete sheet of metal constructed as in Fig. 1.

Fig. 4 is an end view of a modification of Fig. 1.

Referring now with particularity to the drawings, I have shown a metallic element A of elongated form which consists of a main body 1 and a wall 2 upstanding therefrom. The top of the wall 2 is provided with a marginal portion 3 bent or returned toward the main body. The body 1 is adapted to lie upon the ordinary roof sheathing. A cleat consisting of a flat portion 5 with a wall 6 and hook shaped portion 7 is provided, the hook overlying the bend between margin and upstanding wall of the element A, the flat base 5 of the cleat being adapted to be nailed to the roof sheathing as by nail 8, thus securing the element A to the roof.

A second metal element B and having a body 9 and upstanding wall 10 is provided, the element having its marginal portion 11 overlying the marginal portion 3 of the element A. Between the extreme edge of the portion 11 and the bend at the top of the wall 10 an offset lock 12 is provided which when the element B is pressed down over the marginal portion 3 snaps beneath the raw or extreme edge 13 of the margin 3. In this way the element A is secured to the roof by means of the fastening means passing through the cleat and the element B is then secured to the element A so that both members are held to the roof sheathing in an adequate manner, yet without having any nail or fastening means passing through the elements themselves. This prevents leakage.

In case it is desired to separate the parts, the element B may be slid longitudinally of the element A and thus removed therefrom.

In the roof proper constructed of members according to this invention, the element B will have similar, but reversely placed portions corresponding to the wall and margin 10 and 11 at its opposite lateral edge.

This invention is not limited to the form of joint herein shown, in which the covering wall is formed as a part of one of the sections

of the roofing, because the invention in its broad aspect may be carried out in connection with the form shown in Letters Patent of the United States granted to me Nov. 27, 1928, No. 1,693,274, in which the covering wall is in the form of a cap, the application upon which said patent issued being a division of the present application.

What I claim is:

10. 1. A metal joint comprising an element having a main body, a wall portion outstanding therefrom, the said wall portion being preformed with a return bend extending toward the body portion, a second element having an outstanding wall portion and a preformed returned margin, the preformed margin of the second element overlying the preformed bend of the first element, and preformed spaced apart offset resilient locks in the margin of the second element, the edge of said lock engaging and interlocking with the edge of the margin of the first element.
15. 2. A metal joint comprising an element having a main body, a wall portion outstanding therefrom, said portion having a preformed return bent marginal portion extending toward the body portion, means engaging the return bend whereby the entire element may be secured to a roof or the like, a second element overlying the securing means and having a body portion and an outstanding wall portion adjacent the wall portion of the first element, the wall of the second element having a preformed return bent marginal portion, an edge of said marginal portion being resiliently and interlockingly engaged by the edge of the first mentioned marginal portion whereby the second element is anchored upon the securing means for the first element.
20. 3. A metal joint comprising an element having a main body, a wall outstanding from said body and having its margin returned toward the body, a second element having a body and an outstanding wall with a returned margin, the margin of the second element overlying the margin of the first element, a raw edge on one margin engaging a raw edge on the other resiliently and interlockingly.
25. 4. A metal joint comprising an element having a main body, a wall outstanding from said body and having its margin returned toward the body, a second element having a body and an outstanding wall with a returned margin, the margin of the second element overlying the margin of the first element, a raw edge on one margin engaging a raw edge on the other and interlockingly, and resiliently engaging the same, and means engaging the first element for securing the same to a roof or the like.
30. 5. A roof joint comprising a metal element having a flat body adapted to lie upon a roof, a wall upstanding from the body and

having a marginal portion returned toward the body, a securing means having a body, an upstanding wall and a returned margin overlying the first mentioned margin, and a second element having a body overlying the body of the securing means, an upstanding wall adjacent the wall of the first element, and having a margin overlying the margin of the securing means and the first element, a raw edge of the margin of the second element resiliently interlockingly engaging the edge of the margin of the first element.

6. A roof joint comprising a metal element having a flat body adapted to lie upon a roof, a wall upstanding from the body and having a marginal portion returned toward the body, a securing means having a body, an upstanding wall and a returned margin overlying the first mentioned margin, and a second element having a body overlying the body of the securing means, an upstanding wall adjacent the wall of the first element, and having a margin overlying the margin of the securing means and the first element, the margin of the second element interlockingly engaging the edge of the margin of the first element by means of a punched out resilient lock located between the edge of the margin of the second element and the ridge formed by the bend of the margin, the edge of the lock engaging the edge of margin of the first mentioned element.

7. A roof joint comprising metallic sections, the adjacent longitudinal edge portion of each section having an upstanding wall, the wall of one section having a portion overlying a portion of the wall of the other section, an offset resilient lock in one wall portion opposing a raw edge of the other wall portion, said lock comprising a preformed member having its upper edge substantially at the same level as the said raw edge to snap under and into engagement with the same when the overlying wall portion is pressed downwardly.

8. A roof joint comprising metallic sections, the adjacent edge portion of each section having an upstanding wall, a portion of the wall of one section overlying a portion of the wall of the other section, an offset lock in one wall portion engaging an edge of the other wall portion, the engaging edge of the lock merging with the face of the wall portion from which it is offset, said lock comprising a preformed member having its upper edge substantially at the same level as the said edge of the other wall to snap under and into engagement with the same when the overlying wall portion is pressed downwardly.

In testimony whereof, I affix my signature,
EBER J. HAYMAN.
